CYCLE SADDLE

Richard M. Timms, Memphis, Tenn., assignor to Troxel Manufacturing Company, Moscow, Tenn., a corporation of Ohio

Filed July 3, 1964, Ser. No. 80,693

Term of patent 14 years

(Cl. D90—16)

FIG. 1

FIG. 2

FIG. 4

FIG. 3

FIG. 1 is a perspective view of a cycle saddle showing my new design.

FIG. 2 is a side elevational view thereof.

FIG. 3 is a plan view thereof.

FIG. 4 is a fragmentary sectional view taken as on the line IV-IV of FIG. 1.

I claim:

The ornamental design for a cycle saddle, as shown.
